UNITED STATES PATENT OFFICE

2,368,096

PICTURE TRANSMITTING APPARATUS

Alda V. Bedford, Collingswood, N. J., assignor to
Radio Corporation of America, a corporation
of Delaware

Original application April 20, 1938, Serial No.
203,015. Divided and this application January
15, 1942, Serial No. 426,811

8 Claims. (Cl. 178—7.2)

This application is a division of application Serial No. 203,015, filed April 20, 1938, now Patent No. 2,292,816, granted Aug. 11, 1942, in the name of Alda V. Bedford, and entitled "Picture transmitting apparatus." The invention relates to the transmission of electrical signals such as picture signals and particularly to a picture transmitter designed to transmit the direct current component of picture signals.

It has been found advantageous in television systems to transmit all frequency components of the picture signals down to and including zero frequency, that is, direct current. The principal advantage of such transmission is that the large power tubes of the transmitter are used more efficiently for reasons which need not be discussed here.

Transmission of the direct current and very low frequency components of signals cannot be effected conveniently by employing direct current amplifiers in the entire amplifier channel from the input to the output of the transmitter. As is well known, it is much easier to design satisfactory A.-C. amplifiers than to design satisfactory D.-C. amplifiers, especially if the amplifier must give uniform gain over a wide frequency band of the character required in television transmission.

It is, accordingly, an object of my invention to provide an improved method of and means for transmitting the direct current and low frequency components of picture signals.

A further object of my invention is to provide an improved method of and means for reducing the effects of low frequency disturbances in a picture transmitter.

In the preferred embodiment of my invention, as applied to a television transmitter, horizontal synchronizing impulses are produced at the end of each scanning line and vertical synchronizing or framing impulses are produced at the end of each picture frame. The synchronizing impulses are mixed with the picture signals for transmission therewith.

Suitable means is employed to make the synchronizing impulses have a predetermined amplitude with respect to "black" in the picture signal before they and the picture signals are passed through the main A.-C. amplifier of the transmitter.

After the signals have passed through the main A.-C. amplifier, the synchronizing impulses would no longer have their original amplitude (because of the loss of the D.-C. and low frequency components) unless a special circuit were

employed for restoring their original amplitude and thus restoring the lost components.

In accordance with one of the preferred embodiments of my invention this restoration of lost components is accomplished by supplying the carrier wave, after it has been modulated by the picture signals and synchronizing impulses, to a biased rectifier circuit. This circuit is so adjusted that when the modulated carrier wave exceeds a predetermined amplitude it is rectified and fed back to a D.-C. portion of the transmitter amplifier channel to reduce the amplitude of the carrier wave. The carrier wave peaks which are rectified are the peaks representing synchronizing pulses. In this way the synchronizing impulses are restored to their original amplitude whereby the lost D.-C. and low frequency components are restored. The present application relates particularly to the use of additional control impulses in the restoring circuit.

Other objects, feature and advantages of my invention will appear from the following description taken in connection with the accompanying drawings in which

25 Figure 1 is a block diagram of a preferred embodiment of my invention,

Figure 2 is a circuit diagram of the embodiment shown in Figure 1,

Figure 3 is a curve which is referred to in explaining the invention, and

30 Figures 4a, 4b and 4c are curves which are referred to in explaining one way in which the apparatus shown in Fig. 2 may be operated.

Referring to Fig. 1, one embodiment of my invention is shown applied to a television transmitter which comprises suitable means represented by the block 1 for generating picture signals and synchronizing impulses. The apparatus indicated by reference numeral 1 may be designed in accordance with the teachings of my Patent 2,192,121, issued February 27, 1940, entitled "Television systems and the method of operation thereof," and assigned to the Radio Corporation of America. The important feature of its design is that the synchronizing signals have a predetermined amplitude with respect to "black" in the picture.

The output of block 1 is represented by the curve 2. It is a composite signal comprising picture signals 2a, and synchronizing impulses 2b which, in the illustration, are the horizontal synchronizing impulses. The output of block 1, in the example being described, is the same as the output supplied to the transmitter 168 of my above-mentioned patent. The apparatus in the block

1 may be identical with the apparatus shown in the said copending application which supplies a composite signal to the said radio transmitter 168.

It will be noted that in curve 2 each synchronizing impulse consists of a "pedestal" which always comes to the "black" picture level and a "super-sync" impulse which is set on the front edge thereof.

It should be understood that this specific kind of synchronizing signal is not necessary in practicing my invention, that is, the pedestal may be omitted. For example, British Patent 406,672, filed August 31, 1932, shows how to produce background "control" impulses which always reach a level representing "black" in the picture. My synchronizing impulses may be generated in this same way, if desired.

Or, the composite signal may be generated as taught by French Patent 738,475, having the delivery date of October 17, 1932, where the peak of each synchronizing impulse goes to a fixed value beyond "black" in the picture.

The signal supplied by block 1 is impressed upon an alternating current amplifier 4 which greatly amplifies the composite signal. Amplifier 4 is a high gain, wide band pass amplifier which could not easily be designed to pass direct current.

The amplified signal appearing in the output of amplifier 4 no longer contains the direct current and low frequency components. The lost components are restored as follows: The output of amplifier 4 is supplied to a direct current amplifier 36 and next impressed upon a suitable modulator 37 for modulating a carrier wave supplied by an oscillator 38.

The lost direct current and low frequency components are inserted by means of a feedback circuit which derives the negative feedback control voltage from the modulated carrier wave. The negative feedback circuit includes suitable rectifiers, biasing sources and filters indicated at 39 and a direct current amplifier indicated at 41.

The preferred embodiment will be better understood by referring to Fig. 2 where parts similar to those in Fig. 1 are indicated by like reference numerals.

Referring to Fig. 2, the amplifier 36 comprises an amplifier tube 42 which is direct current coupled to the input circuit of the modulator 37 comprising amplifier tubes 43 and 44 connected in push-pull relation.

In this embodiment of the invention (assuming negative modulation) the number of stages in the amplifier 4 is such that the synchronizing impulses when impressed upon the grid of the amplifier tube 42 are of negative polarity. Therefore, they appear on the control grids of modulator tubes 43 and 44 with a positive polarity whereby they cause an increase in the amplitude of the radiated carrier wave. The carrier wave supplied by the oscillator 38 is also supplied to the input circuit of modulator tubes 43 and 44 whereby the carrier wave is modulated by the video output of the tube 42 in a well known manner. This modulated carrier wave appears in the tank circuit 46 of the modulator whereby it may be supplied over a transmission line or the like to the antenna or other load.

The signal which it is desired to radiate and which contains the direct current and low frequency components is illustrated in Fig. 3. It will be seen that the maximum amplitude of

the modulated carrier wave represents the synchronizing impulses and that all these impulses come to a fixed value with respect to the predetermined "black" level. It will be understood

5 that without the action of a direct current reinserting circuit, the signal would not have the character shown in Fig. 3 but instead the carrier wave representative of synchronizing impulses would not be at the "black" level.

10 In accordance with one feature of my invention, I reinsert the direct current and low frequency components by rectifying the carrier wave representative of synchronizing impulses when it exceeds a certain predetermined value and feeding back this rectified voltage to the direct current amplifier 26. I accomplish this 15 by means of a rectifier 47 which is coupled to the tank circuit 46 through an inductance coil 48. Rectifier 47 and coil 48 are connected in 20 series with a biasing battery, or the like, 49, these in turn being connected in series through switches 51 and 52 to a filter resistor 53 shunted by a filter condenser 54.

With the switches 51 and 52 in the position 25 illustrated, for direct current transmission, whenever the carrier wave voltage impressed upon the rectifier 47 exceeds the negative biasing voltage of battery 49 a charging current will flow into the filter condenser 54. Because of 30 the time constant of the circuit comprising condenser 54 and resistor 53, the periodic current flow into condenser 54 caused by recurring synchronizing impulses will be substantially steady direct current. This current may be further 35 filtered by means of a filter coil 56 and filter resistor 57.

The control voltage appearing across resistor 57 is supplied through conductors 58 and 59 to the input circuit of the direct current amplifier 41. The amplifier 41 comprises tubes 61 and 62 coupled in any suitable manner for transmitting direct current.

The input circuit of tube 61 includes variable biasing means 63 and a switch 64 which is shown in position for direct current transmission. As 45 will be explained later, it may be moved to a position for alternating current transmission, the control voltage in this case being fed back through a coupling condenser 65.

The output circuit of the tube 62 preferably 50 includes a filter comprising a resistor 66 and a condenser 67 for further filtering the feedback control voltage. The plate of the tube 62 is connected through a conductor 68 to the control grid of amplifier tube 42 whereby the direct 55 current output of amplifier 41 biases the tube 42 and thus controls its direct current output.

From the foregoing description it will be seen that, with the switches in the positions illustrated in Fig. 2, the television transmitter will 60 transmit the direct current and low frequency components for the condition of negative modulation of the carrier wave by the synchronizing impulses, that is, for the condition where the synchronizing impulses increase the amplitude 65 of the carrier wave. The circuit is adjusted for proper operation by adjusting a biasing battery 71 in the input circuit of the modulator and by adjusting the value of biasing battery 49 so that when the carrier wave is being modulated by a dark signal there is little or no flow 70 of current through the rectifier 47. The adjustments are also made such that the synchronizing peaks cause the maximum carrier which is desired for any picture condition. Now, when 75 a light signal (as distinguished from a dark

one) modulates the carrier wave, the peak amplitude of the carrier representing the synchronizing impulses increases to cause charging current to flow into condenser 54 whereby a positive voltage is supplied over conductor 59 to the grid of tube 61. This in turn makes the control grid of tube 42 more positive whereby the control grids of tubes 43 and 44 are made more negative and whereby the peak value of the carrier wave is held down to approximately the original pre-set level.

It will be understood that the above described circuits will remove low frequency disturbances which are introduced at points in the transmitter following the equipment represented by the block 1. For example, if a low frequency disturbance, such as a 60 cycle ripple, occurs in the amplifier 4, or in the oscillator 38, it will cause the synchronizing impulses to follow the form of this sine wave and the D. C. reinserting circuit which follows will remove the 60 cycle ripple by again levelling off the synchronizing impulses.

It may be desirable to transmit picture signals without the direct current component but still retain the property of my improved system to buck out low frequency interference and accurately restore low frequency response. To operate the system of Fig. 2 in this manner, switches 51 and 64 are thrown to the dotted line A.-C. positions. With the switch 51 in the A.-C. position, the biasing battery 49 is removed from the circuit and there is substituted therefor a filter comprising a resistor 72 and a condenser 73. In this case, the condenser 73 gradually charges up to any value required to substantially stop the synchronizing peaks from causing current flow through rectifier 47 so that the voltage across resistor 57 is merely an indication of the height of the impulses. The signal across resistor 57 reaches the direct current amplifier 41 through the coupling condenser 65 which transmits only the A.-C. components. The low frequency component of this alternating current progresses through the negative regeneration loop and tends to hold the impulse peaks to a value which is permitted to drift or change only at a very low frequency rate.

In accordance with still another embodiment of my invention, the switch 52 may be thrown to the right hand position to produce the feedback signal illustrated in Fig. 4c whereby a control voltage or pilot signal is derived from impulse 96 which are set on top of the pedestals. This type of control may be employed for either A.-C. or D.-C. transmission.

The signal of Fig. 4c is produced by adding the signal of Fig. 4a (representing one side or polarity of a modulated carrier) which appears in the tank circuit 46 and the signal of Fig. 4b which appears across a resistor 97. The side of the carrier represented by Fig. 4c is rectified by the rectifier 47, but because of the biasing battery 49 (or filter 72-73) only the peaks of impulses 96 pass through the rectifier to charge condenser 54.

The impulses 96 may be derived from the horizontal synchronizing impulses supplied from unit 1 and passed through a phase shifter or delay network 98 and amplifier and/or modulator 99 to the resistor 97.

When the control is derived from impulses 96 the pedestals are maintained at a fixed level regardless of what happens to the "super-sync" impulses. This would be useful in case the "super-sync" impulses were subjected to saturation or other alteration causing them to be unsuited for

the purpose of reinserting D.-C. and low frequency components.

It should be noted that the signal represented in Fig. 4a is the one which is radiated to a receiver even though the signal of Fig. 4c is used in the feedback control.

It may be noted that additional intelligence or information may be transmitted by modulating the impulses 96 before they are impressed across the resistor 97. The effect of such modulation is to introduce an additional modulation on the transmitted composite signal comprising picture signal and synchronizing impulses. At the television receiver, this modulation is removed before the signal is impressed upon the cathode ray tube by means of a leveling or D.-C. reinserting circuit such as that disclosed in Patent 2,252,746, issued August 19, 1941, to P. W. Willans. For example, a control tone for a volume expander could be transmitted in this way. It would be taken from a portion of the receiver circuit preceding the leveling or D.-C. reinserting stage.

I claim as my invention:

1. In combination, means for producing a composite signal comprising picture signals and periodically recurring control signals wherein said control signals reach a predetermined level when said composite signal contains the desired components and does not contain undesired components, a translating device having an input circuit and an output circuit and being capable of transmitting low frequency components, means for impressing said composite signal upon said input circuit, a degenerative feedback circuit having an input circuit and an output circuit and being capable of transmitting said low frequency components, means for producing periodically recurring control impulses, means for adding said control impulses to the control signals which appear in the output circuit of said translating device to produce a feedback control signal, means for deriving from said feedback control signal a D.-C. voltage having a value which is a measure of the amount said periodically recurring control signals depart from said level, means for impressing said D.-C. voltage upon the input circuit of said feedback circuit, and means for coupling the output circuit of said feedback circuit to the input circuit of said translating device.

2. The invention according to claim 1 characterized in that said means for adding said impulses and said control signals and said means for deriving said feedback control signal comprises a coupling device, a resistor, a rectifier and a condenser in series said resistor being connected across said source of control impulses, said coupling device being coupled to the output circuit of said translating device, and a resistor connected across said condenser and having such resistance that said condenser discharges only a slight amount between the occurrence of successive control impulses.

3. The invention according to claim 1 characterized in that additional means is provided for modulating said control impulses whereby an additional modulation is placed on said composite signal.

4. In combination, means for producing a composite signal comprising picture signals, pedestals and periodically recurring synchronizing pulses wherein said synchronizing pulses are set on said pedestals and wherein said pedestals reach a predetermined level when said composite signal contains the desired components and does not contain undesired components, modulating means

for modulating a carrier wave by said composite signal, said modulating means having an input circuit and an output circuit and being capable of transmitting low frequency components, means for impressing said composite signal upon said input circuit, a degenerative feedback circuit having an input circuit and an output circuit and being capable of transmitting said low frequency components, means for producing periodically recurring control impulses, means for adding said control impulses to the portions of said modulated carrier which are representative of said pedestals and with said control impulses adjacent to and of greater amplitude than said synchronizing pulses to produce a feedback control signal, means for deriving from said feedback control signal a D.-C. voltage having a value which is a measure of the amount said periodically recurring pedestals depart from said level, means for impressing said D.-C. voltage upon the input circuit of said feedback circuit, and means for coupling the output circuit of said feedback circuit to the input circuit of said modulating means.

5. The method of signal transmission which comprises producing a signal which periodically reaches a predetermined level when it contains the desired components and does not contain undesired components, amplifying said signal and simultaneously causing an undesired loss of low frequency components, modulating a carrier wave by said amplified signal whereby there is produced a modulated carrier wave having portions representative of said periodically recurring signal portions, producing impulses which recur periodically at the same rate as said recurring signal portions, adding said modulated carrier portions and said impulses to produce recurring control signals, deriving from said control signals a comparatively steady D.-C. voltage which is a measure of the amount said modulated carrier wave portions depart from said level, and utilizing said D.-C. voltage to counteract the departure of said carrier wave portions from said level.

6. The method of signal transmission which comprises producing a signal which periodically reaches a predetermined level when it contains the desired components and does not contain undesired components, amplifying said signal and simultaneously causing an undesired loss of low frequency components, modulating a carrier wave by said amplified signal whereby there is produced a modulated carrier wave having portions representative of said periodically recurring signal portions, producing impulses that are of substantially constant amplitude and which recur periodically at the same rate as said recurring

signal portions, adding said modulated carrier portions and said impulses to produce recurring control signals, deriving from said control signals a comparatively steady D.-C. voltage which is a measure of the amount said modulated carrier wave portions depart from said level, and utilizing said D.-C. voltage to counteract the departure of said carrier wave portions from said level.

10 7. The method of signal transmission which comprises producing a signal which periodically reaches a predetermined level when it contains the desired components and does not contain undesired components, amplifying said signal and simultaneously causing an undesired loss of low frequency components, modulating a carrier wave by said amplified signal whereby there is produced a modulated carrier wave having portions representative of said periodically recurring signal portions, producing impulses which recur periodically at the same rate as said recurring signal portions, modulating said periodically recurring impulses whereby an additional modulation is put on the transmitted signal, adding said modulated carrier portions and said impulses to produce recurring control signals, deriving from said control signals a comparatively steady D.-C. voltage which is a measure of the amount said modulated carrier wave portions depart from said level, and utilizing said D.-C. voltage to counteract the departure of said carrier wave portions from said level.

20 8. In combination, an amplifier system having an input circuit and an output circuit, a source of signal containing recurring pulses which depart from a reference voltage by an amount that is proportional to desired components that have been lost or undesired components that have been added in circuits preceding said amplifier system, said source being connected to said input circuit, a source of additional pulses modulated by a certain wave, means for combining said additional pulses and a signal derived from said output circuit in a control circuit with said additional pulses added to or superimposed upon said first pulses, means for producing from said control circuit a pilot signal which is a measure of the deviation of the peaks of said superimposed pulses from a reference voltage, means for filtering said pilot signal to produce a comparatively low frequency signal, means for amplifying said low frequency signal, and means for applying said amplified signal to said input circuit in such phase relation as to reduce said deviation, whereby said certain wave is applied to said input circuit.

ALDA V. BEDFORD.
